The ornamental design for a highlighter, as shown and described.

DESCRIPTION

FIG. 1 is an upper front left perspective view of a highlighter showing my new design;

FIG. 2 is a front elevation view thereof;

FIG. 3 is a bottom plan view thereof;

FIG. 4 is a right side elevation view thereof;

FIG. 5 is a rear elevation view thereof;

FIG. 6 is an enlarged top plan view thereof; and,

FIG. 7 is a left side elevation view thereof.

The broken lines showing the four interior spokes in the top of the cap in FIG. 6 illustrate environmental matter and form no part of the claimed design. The four enclosed broken lines in FIG. 6 which define the bounds of the claim form no part thereof.
